ARMOR PLATE

Louis Henri Denys Marie Ballu, Epernay,
Champigneux, France
Filed Feb. 9, 1961, Ser. No. 38,012
5 Claims. (Cl. 89—36)

Improvements to conventional weapons and the development of the nuclear weapon increase both the diversity and the magnitude of the hazards to which personnel are exposed.

It is consequently necessary that a given material should still better satisfy certain criteria already required for withstanding conventional weapons, that it should ensure maximum weight-saving to facilitate mobility in operational zones and that it should be designed to meet new criteria such as those arising from atomic radiation, for example.

As regards projectiles used by infantry, of which "subversive" warfare tends to increase utilization and hence also the lethal effects in all probability, systematic tests have shown that such projectiles can best be stopped by very hard steels when high impact velocities are involved, and that the fragility factor becomes preponderant at velocities of the order of those associated with small arms.

Furthermore, the steel cores used in "perforating" projectiles have shown liability to fragmentation when they encounter armor of greater surface hardness than their own.

On the other hand, very hard steels present considerable machining and assembling difficulties and display a degree of fragility against high-momentum projectiles and blast effects, and are apt to fatigue through the vibration set up by the firing of automatic weapons or by drive, transmission or propulsive components, etc., since certain structural parts can be subjected to very high frequencies due to the fact that such steels will vibrate at the higher harmonics during sustained vibration, or can be subjected to beats.

When structural and assembly components are produced, as is often the case, from steels difficult to machine, this notably results in a large weight penalty being incurred, as well as local stresses and a certain structural fragility.

Armor plate consisting of layers of differently processed or different grades of steel offer no machining advantages and their performance has not justified their general use.

Armor plate made of the known light alloys is incapable in certain cases—generally when residual velocities exceed 1,000 f.p.s.—of offering a performance comparable to that of steel; on the other hand, performance, assessed in terms of weight of metal per unit of protected area, is in the vast majority of cases superior at velocities below 1,000 f.p.s.

Other objects and many of the attendant advantages of the invention will be readily appreciated as the same becomes better understood by reference to the following description, when considered with the accompanying drawing wherein:

FIGURE 1 shows in cross-section a composite armor constructed in accordance with the invention; and

FIGURE 2 is a perspective view of a pre-armor plate.

Broadly, the armor plate according to this invention is intended for strongpoints in fixed installations, vehicles, ships, etc., and is characterized in that it consists of an inner metal armor plate 10 of easily machinable light alloy of suitable mechanical characteristics to form the walls of the shell or element to be shielded, and in an external pre-armor plate 11 of very hard steel of high elastic limit and sufficiently thick to reduce the velocity

2

of the projectiles which the armor is designed to withstand and to render that velocity low enough so that, after perforating said pre-armor plate, the projectiles are travelling at a velocity low enough for it to be nullified within the thickness of the inner or structural armor plate 10.

These functional components of the armor as a whole are joined together with a layer 12 of cold-vulcanizing elastomer glue, or similar means, after said components have been machined separately by the method most suitable to each, and notably after the complete inner armor plate 10 has been assembled by some appropriate means such as welding in particular.

Machining and assembly of the light alloy shell 10 raises no difficulties and results in no parasite overburdening that does not contribute to protection. Consequently, such a shell can be made tight and the fittings for the necessary mechanical components secured thereto by drilling, tapping and welding.

It will be preferable, in particular, not to fit the pre-armor plate 11 before the remainder of the system has been finished and, where necessary, tested, and to design said pre-armor plate 11 is sufficiently small elements to ensure rational shell architecture, facilitate the expansion permitted by the elastomer joint 12 and reduce the unit weight of the elements to facilitate assembly operations or replacements after perforation.

Such an arrangement assists weight-saving in particular, by permitting as accurate a distribution as required of the thicknesses called for by operational needs or degree of exposure to fire.

The outer armor plates or scales constituted thus may be bevelled as shown at 13 to facilitate lapping, with due account for angles settings most vulnerable to projectile impact angles.

Detachment of the scales, to permit local repairs say, can be achieved for example by injecting a fluid, solvent if necessary, under pressure, with a needle inserted between the pre-armor and the structural armor or passing straight through the latter which is easy to drill and tap to form a hole such as 14.

Pre-armor plate of weight and efficacy differing according to the missions for which the equipment is destined may be provided on a given production-type vehicle body or gun turret.

From the operational standpoint, the weight saving enables dangerous areas and obstacles to be crossed more rapidly and facilitates air transport.

Efficacy of the protection is broadened against:

(1) Anti-personnel or perforating projectiles possessing high kinetic energy, by the provision of successive materials suitable for the residual velocities and for increasing the likelihood of core rupture.

(2) Heavy splinters and projectiles capable of rupturing the pre-armor by high-momentum impact but which expend their energy in deforming the more ductile structural armor plate.

(3) The effects arising from the projection of armor-plate or projectile splinters, the latter being arrested by the inner armor plate.

(4) Blast effects, by reason of the great rigidity of the plates, the resistance to flexure of which for a given weight is high, while the grain flow is virtually neutral in the vicinity of the elastomer.

(5) Combined blast and splinter effects (grenades and shells), as is evident from the previous two paragraphs.

(6) Rupture due to fatigue, vibration being damped by the heterogeneousness of the medium and the hysteresis of the elastomer.

(7) Heat effects from nuclear devices: for a given mass, the heat conductivity per unit area of steel is 35%

higher than that of aluminum. The coefficient of conductivity of the elastomer is half that of the steel, yet its small thickness introduces a dual convection effect.

(8) Gamma radiation, for whereas the "half-value" thicknesses of the steel and the light alloy are substantially inversely proportional to their densities, it is a well-known fact that alloy steels exposed to gamma radiation become radioactive in turn, whereas light alloys decontaminate rapidly.

The armor according to the invention can be made by a method characterized in that the component parts of the inner armor plate and those of the outer armor plate are machined separately and assembled "in situ" after their joining faces have been smeared with the aforementioned elastomer glue, or assembled by some similar means.

It is to be understood that the invention is by no means limited to the embodiments described and illustrated hereinabove by way of example only.

What I claim is:

1. A method of making an armor, said method comprising the steps of forming an inner shell structure of easily machinable light alloy, machining separately plates of extra-hard steel having high elastic strength, bevelling the edges of said plates, and fastening said plates on the outer face of said inner shell structure by means of an elastomer cement compound to obtain an outer pre-armor plating upon said inner shell structure. 25

2. A composite armor adapted to withstand the impact of high-velocity projectiles, comprising an inner 30

shell of easily machinable light alloy having suitable mechanical characteristics, a plurality of outer pre-armor plates of extra-hard steel having high elastic strength and a layer of self-vulcanizing elastomer cement interposed between said inner shell and said outer pre-armor plates, the thickness of the latter being sufficient to reduce the velocity of said projectiles, so that the projectile velocity is low enough after one of said pre-armor plates has been perforated to allow said projectile to have its velocity nullified within the thickness of said inner shell. 10

3. A composite armor according to claim 2, wherein said outer pre-armor plates are fully machined while independent of each other, before final assembly onto said inner shell.

15 4. A composite armor according to claim 3, wherein said pre-armor plates have bevelled registering edges to facilitate their overlapping.

5. A composite armor according to claim 2, wherein orifices are provided in said inner shell for injecting under pressure a solvent of said elastomer cement to dismount at least one of said outer pre-armor plates. 20
